(57) CLAIM

The ornamental design for the stun device for personal defense, as shown and described in the accompanying drawings.

DESCRIPTION

FIG. 1 is a side elevational view of a new design for a stun device for personal defense according to the invention the opposite side view being a mirror image thereof;

FIG. 2 is a top view;

FIG. 3 is a bottom view;

FIG. 4 is a right end view;

FIG. 5 is a left end view;

FIG. 6 is a perspective view; the ghost-line portions shown in FIGS. 1-6 are for the purpose of environment only;

FIG. 7 is a side elevational view similar to FIG. 1 but including an integral handle as part of the claimed design; and,

FIG. 8 is a perspective view similar to FIG. 6 but including the integral handle.
